United States Patent Office

Des. 180,362
Patented May 28, 1957

180,362

GOLFER'S VEHICLE OR THE LIKE

Lee C. Hall, Cincinnati, Ohio

Application September 12, 1955, Serial No. 37,883

Term of patent 14 years

(Cl. D14—3)

Fig. 1 is a side perspective view of the golfer's vehicle or the like, showing my new design.

Fig. 2 is a rear perspective view of the device of Fig. 1.

Fig. 3 is a front perspective view of the device of Figs. 1 and 2.

I claim:

The ornamental design for a golfer's vehicle or the like, as shown.
